ROTATING INTERNAL CONTACT MINIATURE SWITCH

William R. Edwards, California, Md.

Application March 15, 1956, Serial No. 571,843

4 Claims. (Cl. 200—6)

(Granted under Title 35, U. S. Code (1952), sec. 266)

The invention described herein may be manufactured and used by or for the Government of the United States of America for governmental purposes without the payment of any royalties thereon or therefor.

The present invention relates to a multiple position miniature internal contact rotary switch adapted for panel installation and which may be used to control a plurality of electric circuits.

It is an object of the present invention to provide a miniature rotary switch of the character described which is of simple construction and few parts and that may be easily and inexpensively manufactured.

It is a further object of the present invention to provide a miniature rotary switch of the character described which is of compact size particularly adapted for applications where space is limited.

It is a further object of the present invention to provide a miniature rotary switch of the character described that is of sturdy construction to provide reliable, trouble-free operation.

Other objects and many of the attendant advantages of the present invention will be readily appreciated as the same becomes better understood by reference to the following detailed description when considered in connection with the accompanying drawings wherein:

Fig. 1 is a partial vertical section of a preferred embodiment of the invention.

Fig. 2 is a section of the contact housing and actuator along line 2—2 of Fig. 1.

Fig. 3 is a partial vertical section of a second embodiment of the invention.

Fig. 4 is a section of the contact housing and actuator along line 4—4 of Fig. 3.

Fig. 5 is a partial vertical section of a third embodiment of the invention.

Fig. 6 is a section of the contact housing and actuator along line 6—6 of Fig. 5.

Fig. 7 is a partial vertical section of a fourth embodiment of the invention.

Fig. 8 is a section along line 8—8 of Fig. 7.

Fig. 9 is a section of the contact housing and actuator along line 9—9 of Fig. 7.

Referring now to the drawings, wherein like reference characters designate like or corresponding parts throughout the several views, there is shown in Fig. 1 a cup shaped, insulative, contact housing, generally indicated by the reference numeral 11, having a disc shaped end portion 12, and a threaded tubular portion 13. Peripheral stationary contacts 14, of palladium coated wire, for example, are imbedded in and circumferentially spaced about the interior surface of tubular portion 13. An axial contact 15 is accommodated by end portion 12. A cylindrical actuator of insulative material, generally indicated by reference numeral 16, has a handle portion 17, a central portion 18 of enlarged diameter provided with a transverse bore 19, and an end portion 20 rotatably received within contact housing 11. One face of central

2

portion 18 abuts the rim of contact housing 11. A rectangularly shaped spring contact 21, preferably formed from palladium wire, is located in a rectangular groove or notch 22 in end portion 20. Spring contact 21 resiliently engages axial contact 15 and is selectively and resiliently engageable with peripheral contacts 14 upon rotation of actuator 16. All contact surfaces are preferably rhodium plated. A sleeve 23 encompasses central portion 18 and a part of tubular portion 13. Sleeve 23 is provided with a flange 24 abutting the other face of central portion 18. A pin 25 passes transversely through sleeve 23 and engages tubular portion 13 whereby relative longitudinal displacement of contact housing 11 and actuator 16 is prevented. Sleeve 23 has formed therein a plurality of circumferentially spaced indentations 26 lying in the plane of bore 19. Indentations 26 equal in number peripheral contacts 14 and are oriented therewith. A spring pressed ball detent is located in bore 19 and is engageable with indentations 26 whereby actuator 16 may be resiliently retained in each of a plurality of contact engaging positions. Contact housing 11 may be passed through an aperture of suitable diameter in a mounting panel (shown in dotted lines) and retained therein by a nut 27.

25 The embodiment of the invention shown in Figs. 3 and 4 is similar to the embodiment shown in Figs. 1 and 2, but, the end portion 40 of actuator 36 has been modified to accommodate a spring contact 41 having a straight central portion 42 and arcuate end portions 43 and 44, 30 which latter lie on the cylindrical surface of end portion 40. Spring contact 41 is in a plane perpendicular to the axis of actuator 36. End portions 43, 44 are each of sufficient length to bridge two or more of peripheral contacts 34.

35 In the embodiment of the invention shown in Figs. 5 and 6, tubular portion 53 of contact housing 51 is of a length sufficient to accommodate a plurality of circumferentially spaced rows of contacts 54. Each row of contacts 54 lies in a plane which includes the axis of contact housing 51. End portion 60 of actuator 56 has been modified to accommodate a spring contact 61 having a straight central portion 62 and straight spaced parallel end portions 63 and 64 which lie in a plane including the axis of actuator 56. Contact end portions 63, 64 are of a length sufficient to bridge all of the contacts of any of the peripheral rows of contacts 54. While no axial contact has been shown, end portion 52 of contact housing 51 is provided with a recess 55 to accommodate an axial contact should the inclusion thereof be desirable.

40 Figs. 7, 8 and 9 show an embodiment of the invention adapted to control simultaneously each of two sets of independent circuits. In addition to spring contact 81, similar in all respects to spring contact 61, the embodiment of Figs. 7, 8 and 9 also includes a second spring contact

55 61, the embodiment of Figs. 7, 8 and 9 also includes a second spring contact 91 similar in appearance to spring contacts 61 and 81 but having end portions 93, 94 of increased length which may terminate in retaining fingers 95, 96. Housing 71 is of sufficient length to accommodate

60 the additional contact 91. An insulative plug 97 having a slot in one face thereof to accommodate the central portion 92 of contact 91 is provided to electrically separate contacts 81 and 91. In an alternative form of construction, end portion 80 of actuator 76 may be provided with two respectively perpendicular slots in the face thereof with one slot being of greater depth than the other.

65 Obviously many modifications and variations of the present invention are possible in the light of the above teachings. It is therefore to be understood that within the scope of the appended claims the invention may be practiced otherwise than as specifically described.

What is claimed is:

1. A miniature rotary switch comprising: a cup shaped contact housing provided with a plurality of contacts circumferentially spaced about the axis of said housing on the interior surface of the depending portion thereof, said contacts each comprising a wire end embedded in said housing, a central contact comprising a wire end embedded in the bottom portion of said housing on the axis thereof, an actuator having one end thereof rotatably received by said contact housing, resilient contact means supported by said actuator adjacent said one end in contact with said central contact and selectively engageable with said circumferentially spaced contacts upon rotation of said actuator, said actuator having an enlarged central portion provided with a transverse bore and having a face abutting the rim of said contact housing, a spring and ball detent means in said bore, a sleeve encompassing said enlarged central portion and at least a portion of said contact housing, said sleeve having a flange abutting the other face of said enlarged central portion remote from said contact housing, and a fastener element extending transversely of said sleeve and engaging said contact housing whereby relative longitudinal displacement of said contact housing and said actuator is prevented, said sleeve being provided with a plurality of circumferentially spaced indentations in the plane of said spring and ball detent means and oriented with respect to said plurality of contacts whereby said actuator may be resiliently retained in each of a plurality of contact engaging positions.

2. A miniature rotary switch comprising: a cylindrical cup shaped contact housing provided with an axial contact in the end portion thereof and a plurality of circumferentially spaced contacts on the interior surface of the tubular portion thereof, a cylindrical actuator having one end thereof rotatably received by said contact housing, a recess provided in said one end of said actuator in a plane including the axis of said actuator, and a resilient contact member in said recess in engagement with said axial contact and selectively engageable with said circumferentially spaced contacts upon rotation of said actuator,

said resilient contact member comprising a spring contact member having two pairs of straight, spaced, parallel sides with at least two of said sides being perpendicular to each other.

5 3. A miniature rotary switch comprising: a cylindrical cup shaped contact housing provided with a plurality of circumferentially spaced rows of contacts disposed on the interior surface of the tubular portion of said contact housing, said rows of contacts lying in planes including the axis of said contact housing, a cylindrical actuator having one end thereof rotatably received by said contact housing, and a resilient contact means supported by said actuator adjacent said one end and selectively engageable with said circumferentially spaced rows of contacts upon rotation of said actuator, said resilient contact means comprising a spring wire contact member having a straight central portion and spaced parallel end portions perpendicular to said straight central portion, said end portions lying on the cylindrical surface of said actuator in a plane including the axis of said actuator.

10 4. The combination of claim 3 wherein: said resilient contact means further comprises a second spring wire contact member having a configuration identical to said first mentioned spring contact member, the end portions of said second spring contact member lying on the cylindrical surface of said actuator in a plane including the axis of said actuator and perpendicular to the plane of said first mentioned spring contact member.
